UNITED STATES PATENT OFFICE.

WILLIAM JOHNSON, OF MILWAUKEE, WISCONSIN.

MILLSTONE-DRIVER.

SPECIFICATION forming part of Letters Patent No. 224,291, dated February 10, 1880.

Application filed November 21, 1878.

To all whom it may concern:

Be it known that I, WILLIAM JOHNSON, of Milwaukee, in the county of Milwaukee and State of Wisconsin, have invented certain new and useful Improvements in Millstone-Drivers; and I do hereby declare the following to be a full, clear, and exact description thereof, reference being had to the accompanying drawings, and to the letters of reference marked thereon.

10 The nature of my invention consists in the construction and arrangement of a millstone-driver whereby a millstone may be run true and even, so as to make good and uniform flour, as will be hereinafter more fully set forth.

15 In order to enable others skilled in the art to which my invention appertains to make and use the same, I will now proceed to describe its construction and operation, referring to the annexed drawings, which form a part of this

20 specification, and in which—

Figure 1 is a perspective view of my improved millstone-driver with cap partially removed. Fig. 2 is a side view, and Fig. 3 a central vertical section, of the same. Fig. 4 is a plan view of the bed of the driver. Fig. 25 5 is a plan view, partly in section, of the link and pivoted jaws. Fig. 6 is a plan view of the entire driver.

A represents the bed of the driver, constructed substantially in the form shown in Fig. 4, and formed with a central opening, *a*, for the passage of the mill-spindle. Around this opening is a raised rim or flange, *c*, and in the center, at the outside, and each end of this flange is a raised projection, *B*, for the link to slide upon. On each side of each projection is a wooden bearing, *D*, for the link to bear against.

E represents the link fitting around the rim 40 *C*, and having recesses in its under side to fit over the projections *B*, with their wooden side bearings, *D*. To the link *E* are pivoted four jaws, *F*, by means of pins *G*, which admit of said jaws turning or oscillating up and down for a limited distance, for the purpose of allowing the stone to be kept even. Each jaw *F* is provided with a facing, *H*, suitably fastened in place.

The pins *G*, which pivot the jaws, pass 45 through holes that are made larger than said pins, and between all the adjacent shoulders

formed by said jaws and the links are inserted rubber strips *I*, which form elastic or yielding cushions. At the point where the link rubs against the wooden bearings *D* suitable brass 55 facings are to be fastened to the link.

M is a cap or top plate fitting around the upper part of the rim *C*, and fastened to lugs upon the projections *B* of the bed *A* for holding the parts in place.

The mill-spindle passes up through the opening *a* in the bed of the driver and fits therein, so that the driver will turn with the spindle. The jaws *F* are to fit over the ends of the ordinary bail of the stone and come in contact therewith. The link may move in either direction, so as to bear against the bail and drive the stone. If the spindle should be out of tram, the two operating jaws will turn on their pivots to present flat surfaces against the sides 60 of the bail and permit the stone to run parallel with the bed-stone.

It will readily be understood that when the spindle is out of tram one edge of the jaw only will be in contact with the bail—that is, the upper edge on one side and the lower edge on the other side; but by constructing the jaws so as to be capable of rocking they will adjust themselves, and their entire surfaces will rest flat against the sides of the bail. The elastic 65 or yielding cushions interposed between the jaws and link are to prevent any vibration or tremble that otherwise would occur, and also to facilitate the action and adjustment of the pivoted jaws in their movement on the bail to 70 accommodate the cocking of the stone.

I am aware that a millstone-driver has been devised having a sliding link or yoke, provided with pivoted drag-levers linked to the bail, so as to permit automatic adjustment 75 between the stone and driver to accommodate the tilting or cocking of the stone; and also that a driver has been devised wherein a sliding link or yoke has been provided with arms fitting up into the bail, said arms having elastic cushions covered by convex disks, the disks and cushions secured to the arms by horizontal pins; and do not claim such devices, the first-named being objectionable because there is no provision for backlash or reverse driving. It 80 is limited in its capacity to permit automatic adjustment between the driver and stone, and

it does not apply the power to the best advantage. And the second mentioned is objectionable because it depends for its driving contact and adjustment on a convex face, which gives little frictional contact, and is liable to wear the face of the bail irregularly; and, finally, both forms are objectionable in that they demand a special construction of bail adapted to the peculiar form of each driver.

Having thus fully described my invention, what I claim as new, and desire to secure by Letters Patent, is—

1. In a millstone-driver, the sliding link or yoke provided with horizontally-pivoted vertically-oscillating jaws, whereby a compound

motion of the driver is obtained which permits automatic adjustment between the stone and driver without sacrificing an extended contact between the driver and bail, substantially as specified.

2. In a millstone-driver, the combination of the sliding link or yoke, the horizontally-pivoted jaws for engaging with the bail of the stone, and the elastic packings interposed between the jaws and the link, substantially as and for the purpose specified.

WILLIAM JOHNSON.
